UNITED STATES PATENT OFFICE.

JOSEPH GOULBOURN AND FRED RICKS, OF LEICESTER, ENGLAND, ASSIGNEES TO
UNITED SHOE MACHINERY CORPORATION, OF PATERSON, NEW JERSEY, A COR-
PORATION OF NEW JERSEY.

MACHINE FOR USE IN THE MANUFACTURE OF SHOES.

Application filed April 22, 1925, Serial No. 35,126, and in Great Britain May 19, 1924. Renewed
September 18, 1928.

This invention relates to machines for use in the manufacture of boots and shoes, and more particularly to machines for use in shaping shoe uppers, in assembling uppers and insoles in predetermined relation, or in performing both these operations. The invention is herein illustrated in its application to a machine for shaping or molding the heel end portion of an upper off the last over a heel end form and also over an insole to which the molded heel end of the upper is fastened while on the form; but it will be understood that in various novel aspects the invention is not limited to machines of this particular type.

One object of the invention is to provide improved means for tensioning an upper forwardly about a form, having in view the positioning or holding of the upper about the form, so that the operator may have his hands free for other work, and also, as applied to machines for shaping or molding the heel end portion of the upper over the form, the desirability of drawing the upper tightly about the form with more or less stretching and shaping effect thereon before it is clamped to the end and sides of the form. To adapt the machine for operation upon uppers having previously molded toe portions without distorting the molded toe by the upper-tensioning pull, the invention provides upper-tensioning means which takes its tensioning purchase on the upper at a substantial distance rearwardly of the end of the molded toe without distorting engagement with portions nearer the end of the toe. In the construction shown a gripper is provided which grips the upper substantially midway between its opposite sides in a location substantially between the tip line and the lacing slit and is shaped to clear the molded toe in front of the gripped portion of the upper.

The invention further provides novel means for positioning an insole relatively to a form about which the upper is positioned, so that the upper and the insole will be in the right relation when they are fastened together at their heel ends. The construction shown comprises a device on the upper-tensioning gripper so constructed and arranged as to indicate the proper lateral position of the toe end of the insole and thereafter, by engagement with the insole, to hold it in that position and also

to press it rearwardly against the margin of the upper projecting above the heel end form. 55 The machine herein shown is further provided with means for clamping the heel end of the insole on the form after the insole has been thus positioned by engagement with its toe end.

The novel features of the invention will now be more particularly described by reference to the accompanying drawings and pointed out in the claims.

In the drawings, 65 Fig. 1 is a view in front elevation of as much of the machine as it is necessary to show for an understanding of the present invention, with the upper-pulling mechanism removed therefrom;

Fig. 2 is a view in left-hand side elevation of a portion of the structure shown in Fig. 1, and

Fig. 3 is a view in left-hand side elevation of the upper-pulling and insole-positioning 75 means in operative relation to the form.

The invention is herein shown, for illustrative purposes, as embodied in a machine of the same general character as that shown and described in detail in Letters Patent No. 80 1,700,970, granted on February 5, 1929, upon an application of William C. Baxter, except that the machine herein shown is particularly designed for McKay shoe work and is not provided with means for engaging the upper 85 in jig holes to position it relatively to the form.

The machine shown in said Letters Patent is of the twin type, comprising two sets of 90 operating instrumentalities for operating respectively upon right and left shoes, but only one of these sets of instrumentalities need be and is herein shown for the purpose of an explanation of the present invention. The machine frame comprises a side member 2, a cross tie 4 and a top 6; and mounted upon a pivot shaft 8 on the frame is a treadle 10 depression of which trips a clutch to start the power operation of the machine, the clutch being automatically released at the end of a 100 complete cycle. The heel end portion of the upper is shaped or molded over a heel end form 12 supported by a rod 14 mounted for lengthwise movement in a form carrier 16 which is pivoted on a short shaft 18 near the base of the machine. Co-operating with the 105

form 12 to shape the upper materials there are provided a heel band 20 and wipers 22. It will be understood that after the upper materials and the insole have been properly positioned upon the form 12 in the manner more particularly hereinafter described, the form carrier 16 is swung rearwardly by the power operation of the machine to carry the shoe materials into the heel band 20, after which the heel band is closed to shape and clamp the upper materials about the form, the wipers are operated to wipe the margin of the materials inwardly over the insole, and tacks are driven to secure the materials to the insole. Subsequently the parts are returned to their starting positions and the upper and insole unit is removed from the form 12. For a more complete understanding of these operations and of the construction of the machine as thus far described reference may be made to the Letters Patent mentioned.

Loosely pivoted for swinging movement about the same shaft 18 upon which the form carrier 16 is mounted is a bracket 24 which has fixed thereto a rod 26 extending upwardly into proximity to the top of the form carrier 16 and having at its upper end a head 28 forked to embrace a bracket 30 which projects forwardly and downwardly from the top 6 of the machine frame. This bracket has a curved lower face and acts as a guide when the rod 26 is swung rearwardly, as will be hereinafter more fully explained. The bracket 30 has at its front end a downwardly projecting portion in which is adjustably mounted a stop screw 32 in position to engage the head 28 and thereby limit forward swinging movement of the rod 26. Mounted upon the rod 26 is a sleeve 34 which may slide upwardly and downwardly on the rod but is held from turning movement by means of a key (not shown). The sleeve 34 is normally pressed upwardly against the head 28 by means of a spring 36 which is located between a collar 38 fast on the rod 26 and the top of a recess in the sleeve in which the spring is located. A treadle 40 which is pivoted upon the shaft 8 is connected by a link 42 to a bracket 44 on the sleeve 34 to move the sleeve downwardly against the resistance of the spring 36 for clamping the insole on the bottom of the form 12, as more fully herein-after explained.

The sleeve 34 is held in any position to which it is lowered by the treadle 40 by means of a clutch member 46 which is fast on a pivot pin 48 mounted to turn in the sleeve 34, the clutch member being arranged to engage a wear plate 50 which is fast on the rod 26. Also fixed to the pin 48 is a lever 52 which is pressed downwardly by a spring plunger 54 in the sleeve 34, the clutch member 46 thus being normally held by the spring plunger 54 in position to lock the sleeve 34 against up-

ward movement on the rod 26. A handle 56 extends forwardly from the lever 52 so that the operator by downward pressure thereon can release the sleeve 34 from the rod 26 at will. In order to release the sleeve automatically at a predetermined time in the cycle of the machine, a cam-controlled lever 58 is provided which by upward movement contacts with and raises the rear end of the lever 52.

Mounted in the bracket 44 is a pivot pin 60 which carries an arm 62 that is normally swung laterally away from the form 12 by means of a spring plunger 64 engaging the bracket 44, such swinging movement of the arm being limited by a slotted link 66 which is pivoted on the sleeve 34. A tongue 68 carried by the arm 62 is arranged to engage, when the arm is swung toward the form 12, with a grooved bracket 70 which is fast on the sleeve 34 to assist in guiding the arm and in rigidly connecting it to the sleeve.

The arm 62 is further provided with a lug 72 having a bore therein adapted to receive a rod 74 fixed on the form carrier 16 after the arm has been swung toward the form and when it is moved downwardly by operation of the treadle 40. In this way both the arm 62 and the sleeve 34 are locked to the form carrier 16 to prevent the arm from swinging laterally of the form and also to cause the arm and the sleeve to swing with the form carrier 16 about the axis of the shaft 18 when the form carrier is swung rearwardly to carry the work into the heel band. The arm 62 is also provided with a slot 76 to receive the bracket 30 when the arm is swung rearwardly with the form carrier 16, thus insuring that the arm will not swing laterally of the form to its idle position until the sleeve 34 and the rod 26 have been swung forwardly, even though the sleeve 34 should be moved upwardly to release the arm from the short shaft 74.

The upper end of the arm 62 is provided with a head 78 having downwardly projecting side flanges 80 between which is mounted upon a pivot 82 a member 84 so arranged that it can rock slightly about its pivot. Slidingly mounted for lengthwise movement in the member 84 is a rod 86 which has fast on its lower end an insole clamping member 88. A spring 90 which bears on the upper end of the rod 86 affords provision for yield when the member 88 is carried downwardly into engagement with an insole, and this spring, by bearing upon the head 78, has a tendency to swing the member 84 about its pivot 82 to a limit determined by a stop screw 92. The member 88 may thus tip lengthwise of the form as it is pressed down on the insole until it becomes seated evenly upon the insole.

Mounted upon the machine frame at 94 is a cam-operated bell-crank lever 96 provided with a roll 98 which at a predetermined time

in the cycle of the machine is swung forwardly to engage a face 100 upon the sleeve 34, this face being then in the position indicated by dotted lines in Fig. 2. By this means the sleeve 34 and the rod 26 are swung forwardly about the shaft 18 until they are past the vertical, and thereafter the parts are swung farther forwardly by gravity until the head 28 engages the stop screw 32.

- 10 The means provided for pulling the upper forwardly about the form 12 and for engaging the toe end of the insole to assist in positioning it relatively to the form and the upper are illustrated particularly in Fig. 3.
- 15 On the front upper portion of the form carrier 16 is a boss 102 (Figs. 1 and 3) which is shaped to provide a vertical guideway 104 for a bracket 106 that has mounted in it a pinion 108 arranged to engage rack teeth 110 formed on the boss 102. The pinion 108 is rotated by a hand wheel 112 to raise or lower the bracket 106, and suitable means (not shown) is provided for locking the hand wheel so as to hold the bracket in adjusted position.
- 20 At its upper end the bracket 106 is provided with a head 114 in which there is mounted for movement at right angles to the guideway 104 a gripper carrier 116 provided with rack teeth 118 engaged by a pinion 120 in the head 114. This pinion is turned by a hand wheel 122 to adjust the gripper carrier 116 lengthwise of the shoe upper, and suitable means (not shown) is provided for holding the hand wheel in adjusted position.
- 25 The front end of the gripper carrier 116 is in the shape of a forked head which is embraced by the forked lower end of a member 124 pivotally mounted on a spindle 126 in the forked head. Pivoted in the lower ends of the forks of the member 124 is a pin 128 into which is threaded a screw 130 which passes through a recessed lug 132 depending from the carrier 116. A spring 134 surrounding the screw 130 is located within the recess of the lug 132 and presses the pin 128 forwardly. The upper end of the member 124 has a projection 136 which carries a pad 138 of yielding material and is adapted to serve as one of a pair of gripper jaws. Pivotally mounted at 140 on another projection of the member 124 is a curved arm 142 which serves as the other gripper jaw. One end of the arm 142 is connected by a link 144 to an arm 146 of a bell-crank lever which is pivotally mounted on the spindle 126. The other arm 148 of the bell-crank lever is connected by means of a rod 150 to a treadle (not shown), so that by depression of the treadle the gripper jaw 142 is first swung into gripping relation to the jaw 136 and then by continued movement of the treadle the gripper jaws are swung about the spindle 126 to pull the upper forwardly. A spring 152 connected at its opposite ends to the member 124 and to the lever arm 148 serves to hold the

gripper jaw 142 initially in an idle position widely separated from the jaw 136 so that the molded toe portion of the upper may be readily inserted between the jaws. For holding the gripper jaws in upper-tensioning 70 position the lever arm 148 has pivotally mounted thereon a spring-held pawl 154 which is arranged to engage ratchet teeth 156 formed on a forward extension of the carrier 116. The pawl is provided with a 75 tail portion so that the operator can release it when desired, the parts then returning to inoperative position under the action of the springs 134 and 152.

The gripper jaws 136 and 142 are large 80 enough to engage the upper over a substantial area rearwardly of the tip line and are arranged to engage the upper, for the most part at least, at the rear of the previously molded toe portion, the jaws being also so 85 shaped as to clear the portion of the upper which is located in front of their gripping faces. There is thus no danger of distorting the previously molded toe portion of the upper in pulling the upper forwardly about 90 the form. It will further be seen that the tension is applied to the upper in a location which includes a considerable area of the upper midway between its opposite side portions in front of the lacing slit, so that the 95 gripper is very effective in drawing the upper forwardly to seat it snugly against the back and the sides of the form 12.

After the upper has been thus tensioned about the form 12, the heel end of an insole 100 is placed upon the form and is engaged with the upstanding margin of the tensioned upper materials which thus provide an effective abutment against which to press the edge of the insole to locate it in proper position on 105 the form. Further to assist in positioning the insole and in holding it in proper position, there is mounted upon the curved gripper jaw 142 an insole-positioning and holding device comprising an upwardly projecting narrow finger 158 connected by a screw 160 to an offset lug on a bracket 162 which is fast on the jaw 142. The finger 158 is provided with a recess or notch 164 to receive the toe end of the insole, and it is intended that, to assist in determining the proper lateral position of the forepart of the insole, the middle point of the toe end of the insole will be located in engagement with the finger 158 which thus serves as a sight gage. The 110 finger 158 may be rocked about the axis of the screw 160 to adjust it laterally of the form 12 for different styles of shoes where there are differences in the "swing" of the foreparts in relation to the heel parts. It 115 will be noted that the distance between the insole-engaging face of the finger 158 and the rear end of the heel seat face of the form 12 is somewhat less than the length of the insole, so that the latter is somewhat bent at 120 125 130

its forepart when it is positioned by the finger and is thus held under longitudinal compression. In this manner the heel end of the insole is pressed snugly against the upstanding margin of the upper and its toe end is held in frictional engagement with the finger 158 to prevent its displacement until the clamping member 88 is moved into clamping position.

10 In the operation of the machine, an upper having its toe end molded is placed about the form 12 when the form is in its forwardly swung position and is so adjusted by the operator as to position the back seam in proper relation to the form and to cause the proper amount of the upper materials to project above the bottom face of the form. By depression of the treadle rod 150 the forepart of the upper is then gripped by the jaws 136 and 142 and the upper is tensioned about the form, the gripper being locked in tensioning position by the pawl 154. The operator is then free to remove his hands from the upper, which is held in position about the form by the gripper, and he next places the insole upon the form and in proper relation to the insole positioning and holding member 158 in the manner hereinbefore described. The arm 62 is then swung toward the form 20 so as to position the clamp member 88 above the form, and the treadle 40 is depressed to bring the clamp member into clamping engagement with the insole. Upon the starting of the machine by depression of the treadle 10 the form carrier 16 and its upper-tensioning means, together with the arm 62 and the insole-clamping member 88, are swung rearwardly as a unit to carry the form 12 into the heel band which is then closed 30 to shape and clamp the upper about the form. Thereafter the wipers 22 are operated to wipe the margin of the upper inwardly over the heel end of the insole and the tacking mechanism (not shown) is moved into position and is operated to secure the margin of the upper to the insole, as more fully described in the before-mentioned Letters Patent. Between the overwiping and the tacking operations the lever 58 is operated 40 to release the sleeve 34 from the rod 26, and the sleeve is then moved upwardly by its spring 36 to withdraw the clamp member 88 from the insole and to unlock the arm 62 from the rod 74 on the form carrier 16. The roll 98 then acts to swing the sleeve 34 forwardly, and at the end of the forward movement of the sleeve the spring plunger 64 acts to swing the arm 62 laterally to its starting position. In this manner the insole-clamping means is withdrawn from the form so as to make way for the tacking mechanism which comes into position over the form. In the return of the various parts of the machine to starting positions after the tacking 50 operation the form carrier 16 is swung for-

wardly, and thereafter the operator trips the pawl 154 to cause the gripper to open and release the upper, so that the upper and insole unit may be removed from the form.

Various features of the means herein shown 70 for clamping the insole upon the form are not claimed herein, since they are the invention of William C. Baxter and are claimed in a co-pending application Serial No. 19,347, filed on March 30, 1925. 75

While the invention is herein illustrated in its application to McKay shoe work, it will be understood that in various novel and useful aspects it is not limited to that particular kind of work. 80

Having described the invention, what we claim as new and desire to secure by Letters Patent of the United States is:

1. In a machine of the class described, the combination with a form, of means for tensioning forwardly about the form an upper the toe end portion of which has been previously molded substantially to the shape desired for the finished shoe, said upper-tensioning means being constructed and arranged to take its tensioning purchase on the upper at a substantial distance rearwardly of the end of the molded toe without distorting engagement with portions nearer the end of the toe. 95

2. In a machine of the class described, the combination with a form, of means for tensioning forwardly about the form an upper the toe end portion of which has been previously molded substantially to the shape desired for the finished shoe, said tensioning means comprising an upper-pulling device constructed and arranged to take its tensioning purchase on the upper substantially at the rear of the tip line without distorting engagement with portions of the molded toe in front of the tip line. 100

3. In a machine of the class described, the combination with a form, of means for tensioning forwardly about the form an upper the toe end portion of which has been previously molded substantially to the shape desired for the finished shoe, said upper-tensioning means comprising a gripper constructed and arranged relatively to the form to grip the upper substantially midway between its opposite sides in a location spaced a substantial distance rearwardly of the end of the molded toe without distorting engagement with the previously molded portion. 115

4. In a machine of the class described, the combination with a form, of means for tensioning forwardly about the form an upper the toe end portion of which has been previously molded substantially to the shape desired for the finished shoe, said upper-tensioning means comprising a gripper constructed and arranged relatively to the form to grip the upper at the top of the forepart substantially between the tip line and the lacing slit 125 130

with its upper-gripping jaws shaped to prevent distorting engagement with the molded toe in front of the gripped portion of the upper.

5. In a machine of the class described, the combination with a form, of means for tensioning forwardly about the form an upper the toe end portion of which has been previously molded substantially to the shape desired for the finished shoe, said upper-tensioning means comprising an upper-gripping and pulling device constructed and arranged to engage the upper only in a location at the top of the forepart substantially between the 15 tip line and the lacing slit.

6. In a machine of the class described, the combination with a form, of means for tensioning forwardly about the form an upper the toe end portion of which has been previously molded substantially to the shape desired for the finished shoe, said upper-tensioning means comprising a pair of gripper jaws, one having a facing of yieldable material for engaging the outside surface of the 25 upper at the top of the forepart and the other being curved to extend within the upper into gripping relation to the first jaw without distorting engagement with the molded toe in front of the location where the upper is gripped by the jaws.

7. In a machine of the class described, the combination with a form and means for positioning an upper with its heel end portion about the form, of insole-positioning means 35 constructed to position an insole relatively to the form both lengthwise and laterally by engaging the forepart of the insole.

8. In a machine of the class described, the combination with a form and means for positioning an upper with its heel end portion about the form, of means for positioning an insole relatively to the form comprising a member constructed to serve as a gage at the toe end of the insole to indicate the proper 40 lateral position of the forepart of the insole and thereafter to hold the insole against lateral displacement from the position thus determined.

9. In a machine of the class described, the combination with a form and means for positioning an upper with its heel end portion about the form, of means for positioning an insole relatively to the form comprising a finger arranged to serve as a gage to indicate the proper lateral position of the toe end of the insole and having a notch therein to receive the toe end of the insole and hold it frictionally against lateral displacement.

10. In a machine of the class described, the combination with a form and means for positioning an upper with its heel end portion about the form, of means for positioning an insole relatively to the form comprising a member arranged to serve as a gage to indi-

cate the proper lateral position of the toe end of the insole, said member being adjustable laterally of the form.

11. In a machine of the class described, the combination with a form corresponding substantially to the heel end only of a last and means for positioning an upper with its heel end portion about the form, of means for positioning an insole relatively to the form comprising a device constructed to force the insole rearwardly against the heel end of the upper.

12. In a machine of the class described, the combination with a form and means for positioning an upper with its heel end portion about the form, of means for positioning an insole relatively to the form comprising a member arranged to engage the edge of the toe end of the insole and positioned at a distance from the rear end of the form less than the length of the insole so as to subject the insole to bending stress tending to force it rearwardly against the heel end of the upper.

13. In a machine of the class described, the combination with a form and means for positioning an upper with its heel end portion about the form, of means for positioning an insole relatively to the form comprising a member arranged to serve as a gage to indicate the proper lateral position of the toe end of the insole and constructed to hold the insole in the position thus indicated and to press it rearwardly against the heel end of the upper.

14. In a machine of the class described, the combination with a form corresponding substantially to the heel end only of a last, of means for tensioning an upper forwardly about the form, and means for positioning an insole with its heel end in proper relation to the form by engagement with the forepart of the insole.

15. In a machine of the class described, the combination with a form corresponding substantially to the heel end only of a last, of means for tensioning an upper forwardly about the form, and means for holding an insole in predetermined relation to the form by forcing it rearwardly against the heel end of the upper.

16. In a machine of the class described, the combination with a form, of means for tensioning an upper forwardly about the form, and means for positioning an insole relatively to the form, said insole-positioning means being constructed to indicate the proper lateral position of the toe end of the insole and to force the insole rearwardly against the heel end of the upper.

17. In a machine of the class described, the combination with a form corresponding substantially to the heel end only of a last, of means for engaging an upper and an insole respectively, each at its forepart, to pull the

upper forwardly about the form and to press the insole rearwardly over the form against the heel end of the upper.

18. In a machine of the class described, the combination with a form, of means for pulling an upper forwardly about the form, said upper-pulling means comprising a gripper having thereon a device for positioning an insole relatively to the form.

19. In a machine of the class described, the combination with a form, of means for pulling an upper forwardly about the form, said upper-pulling means comprising a gripper having thereon a device for engaging the toe end of an insole and forcing the insole rearwardly against the heel end of the upper.

20. In a machine of the class described, the combination with a form, of a gripper for engaging the forepart of an upper and pulling the upper forwardly about the form, said gripper having thereon an insole-positioning member adapted to serve as a gage to indicate the proper lateral position of the toe end of an insole on the form.

21. In a machine of the class described, the combination with a form, of a gripper for engaging the forepart of an upper and pulling the upper forwardly about the form, said gripper having thereon a finger provided with a notch to receive the toe end of an insole for positioning the insole relatively to the form.

22. In a machine of the class described, the combination with a form, of means for tensioning forwardly about the form an upper the toe end portion of which has been previously molded substantially to the shape desired for the finished shoe, comprising a gripper having a pair of jaws one of which is shaped to project within the previously molded toe portion, said last-named jaw having thereon a device for engaging the toe end of an insole to position the insole relatively to the form.

23. In a machine of the class described, the combination with a form corresponding substantially to the heel end only of a last and means for shaping the heel end portion of an upper over the form and over an insole on the form, of means for positioning the insole with its heel end in proper relation to the form by engagement with the toe end of the insole.

24. In a machine of the class described, the combination with a form and means for shaping the heel end portion of an upper over the form and for laying its margin inwardly over an insole on the form, of means for forcing the insole rearwardly against the margin of the heel end of the upper by engagement with the edge of the insole before said margin is laid inwardly over the insole.

25. In a machine of the class described, the combination with a form and means for shaping the heel end portion of an upper over the form and over an insole on the form, of means

for engaging the edge of the toe end of the insole to position the insole relatively to the form and to press it rearwardly against the heel end of the upper prior to the shaping of the upper over the insole.

70

26. In a machine of the class described, the combination with a form corresponding substantially to the heel end only of a last and means for shaping the heel end portion of an upper over the form and over an insole on the form, of means for tensioning the upper forwardly about the form and for forcing the insole rearwardly against the heel end of the upper prior to the operation of the upper-shaping means upon the upper.

75

27. In a machine of the class described, the combination with a form corresponding substantially to the heel end only of a last and means for shaping the heel end portion of an upper over the form and over an insole on the form, of means for engaging the forepart of the upper end of the insole respectively to tension the upper forwardly about the form and to position the insole in proper relation to the form prior to the operation of the upper-shaping means upon the upper.

80

28. In a machine of the class described, the combination with a form corresponding substantially to the heel end only of a last and means for shaping the heel end portion of an upper over the form and over an insole on the form, of means for positioning the insole in proper relation to the form by engagement with the forepart of the insole, and means for clamping the insole on the form after it has been thus positioned.

95

29. In a machine of the class described, the combination with means for shaping the heel end portion of an upper over a form and over an insole on the form, and a form corresponding substantially to the heel end only of a last and movable to carry the upper and the insole into position for the operation of said upper-shaping means, of a device movable with said form for positioning the insole in proper relation to the form by engaging the forepart of the insole.

100

30. In a machine of the class described, the combination with means for shaping the heel end portion of an upper over a form and over an insole on the form, and a form movable to carry the upper and the insole into position for the operation of said upper-shaping means, of means movable with the form for positioning the insole in proper relation to the form by engagement with the forepart of the insole and for clamping the heel end of the insole upon the bottom of the form.

115

31. In a machine of the class described, the combination with means for shaping the heel end portion of an upper over a form and over an insole on the form, and a form corresponding substantially to the heel end only of a last and movable to carry the upper and the insole into position for the operation of said

125

130

upper-shaping means, of means movable with the form for tensioning the upper forwardly about the form, and means also movable with the form for positioning the insole in proper 5 relation to the form by engagement with the forepart of the insole.

32. In a machine of the class described, the combination with means for shaping the heel end portion of an upper over a form and over 10 an insole on the form, and a form movable to carry the upper and the insole into position for the operation of said upper-shaping means, of means movable with the form for tensioning the upper forwardly about the 15 form and for pressing the insole rearwardly against the heel end of the upper by engagement with the edge of the toe end of the insole.

33. In a machine of the class described, the combination with means for shaping the heel end portion of an upper over a form and over 20 an insole on the form, and a form movable to carry the upper and the insole into position for the operation of said upper-shaping means, of an upper-pulling device movable with the form for tensioning the upper forwardly about the form, said upper-pulling device comprising a gripper having thereon 25 means for positioning the insole relatively to the form by engagement with the forepart of the insole. 30

In testimony whereof we have signed our names to this specification.

JOSEPH GOULDBOURN.
FRED RICKS.
